UNITED STATES PATENT OFFICE.

FREDERICK McCALAIN, OF PITTSBURG, PENNSYLVANIA.

BANKING-BOOK.

No. 827,935.

Specification of Letters Patent.

Patented Aug. 7, 1906.

Application filed March 27, 1905. Serial No. 252,181.

To all whom it may concern:

Be it known that I, FREDERICK McCALAIN, of Pittsburg, Allegheny county, Pennsylvania, have invented a new and useful Banking-Book, of which the following is a full, clear, and exact description, reference being had to the accompanying drawings, forming part of this specification, in which—

Figure 1 is a perspective view of a banking or check book arranged in accordance with my invention. Figs. 2 and 3 show modifications of the form of Fig. 1. Fig. 4 is a plan view of a pocket banking-book constructed in accordance with my invention. Fig. 5 is a perspective view of another form of the invention with the stubs made as leaves separate from the checks, and Fig. 6 is a perspective view showing another form of pocket banking-book.

20 My invention relates to the class of banking-books which contain detachable forms, such as drafts, checks, notes, or like orders or promises to pay or for the transfer of funds, debits and credits, or for due bills and receipts.

The object of the invention is to provide a simple and efficient system for recording transactions and to provide an arrangement which may be easily handled by unskilled persons; also, to provide a book of this character which may be cheaply and economically made and sold.

This application contains subject-matter set forth and claimed in my prior abandoned application, Serial No. 198,553, filed March 17, 1904.

In the drawings, referring to the form of Fig. 1, I show a book having leaves, each leaf consisting of a stub extending the width of the book with a plurality or group of checks forming the remainder of the leaf. The height or width of the stub is equal to the combined height or widths of the checks, thus giving a stub of ample size to receive the collected data relating to the checks and also the collected data relating to deposits made through the period in which the checks attached to this leaf are drawn, the collected deposit data being vertically separated from the form for the check data. In this figure the form for the check data is in the upper portion of the stub, while the form for the deposit data is below it, the columns to receive the figures being preferably in line with each other, as shown. Each set of columns is preferably provided with a space for the to-

5 tals, and the deposit-column is preferably provided with space for subtracting the total checks from the total deposits and a space for the balance to be carried forward to the next stub. In this arrangement the date is to be placed at the left of the deposit, and the line for the deposit may receive the data as to the origin of the deposit. I have shown the collected data for the checks as arranged to receive the check-number, the date, the name of the party to whose order the check is drawn, and the purpose for which the check is drawn. It will further be noted that on the other side of the stub, as shown on the left-hand leaf, lines are ruled to receive miscellaneous entries in regard to any particular transaction. These may or may not be used, as desired. It is intended in this form that when all the checks in the book have been used the covers shall be shortened or cut off to the length of the stubs, or if the book is loosely bound the stubs may be removed and preserved as permanent record for reference.

In Fig. 2 I show a form similar to that of Fig. 1, except that the form for the deposits is above, while the form for the checks is below, this being a reversal from that of Fig. 1.

In Fig. 3 I show a form similar to Fig. 1, except that the form for the deposits is merely ruled, this being again vertically separated from the form for the collected check data, which may be either above or below.

In Fig. 4 I show a pocket check-book which is arranged with two sets of leaves, one set of leaves being checks, while the other set is made up of stubs. In this case again the stub-leaf contains two forms vertically separated from each other, one form being arranged to receive the collected data for the checks and the other form the collected data for the deposits. In books of this class the stub-leaves may be placed between from three or four of the check-leaves, and the stub-leaves may be ruled on the reverse side. If desired, both sides of the stub may be provided with the vertically-separated forms for collected deposit data and collected check data, thus giving one stub-leaf for two groups of single check-leaves. In books of the pocket type I preferably make the stub-leaves slightly smaller as to some dimensions than the check-leaves for ease in opening for using the next successive check.

In Fig. 5 I show a form similar to that of Fig. 1, except that the stubs are formed as leaves separate from the checks. In this

form the stubs alternate with the check-leaves, and the form for the deposit data may again be either above or below the form for the check data.

5. In Fig. 6 I show a form similar to Fig. 4, except that the book opens along its longer dimensions. In this case again the check data is vertically separated from the collected deposit data, either being above.
10. The advantages of my invention result from the arrangement of the forms for the collected check data and collected deposit data, which are separate and distinct. The vertical separating of these forms avoids confusion and enables the system to be easily used by unskilled persons without liability to mistakes. Attention is called to the stub by the designations, and the stubs give a complete history of all transactions of the 20 character for which the book is intended. The two forms may be placed on either side or on both sides of the stubs, the book may be either permanently bound or of the loose-leaf or other desirable type, and many 25 other changes may be made without departing from my invention. By the words "checks" and "deposits" I intend to cover the two classes of transactions generally known as "debit" and "credit," and similarly 30 the word "banking-book" is used in its broad sense to cover books having detachable forms, such as check-books, draft-books, note-books, receipt-books, and the like. While I have shown the two columns as vertically aligned, they may be out of alignment, though in each case the forms are vertically 35 separated.

I claim—

1. A book having leaves, each comprising 40 a stub with a plurality of checks, each stub bearing a form having appropriately-designated spaces to receive the collected data relating to all checks forming a part of the leaf, and a form vertically separated therefrom and having appropriately-designated spaces to receive the collected data for deposits made during the using of the checks attached to said leaf; substantially as described.

2. A book having leaves, each comprising 45 a stub with a plurality of checks, each stub having on the same side thereof a form having appropriately-designated spaces to receive the collected data relating to all the checks forming a part of the leaf, and a form verti-

cally separated therefrom and having appropriately-designed spaces to receive the collected data for deposits made during the using of the checks attached to said leaf; substantially as described. 55

3. A book having leaves, each comprising 60 a stub with a plurality of checks, each stub having on the same side thereof a form having appropriately-designed spaces to receive the collected data relating to all the checks forming a part of the leaf, and a form 65 vertically separated therefrom and having appropriately-designed spaces to receive the collected data for deposits made during the using of the checks attached to said leaf, the stub having lines upon the opposite side 70 thereof for additional memoranda; substantially as described.

4. A book having leaves, each comprising 75 a stub with a plurality of checks, each stub having on the same side thereof a form having appropriately-designed spaces to receive the collected data relating to all checks forming a part of the leaf, and a form vertically separated therefrom and having appropriately-designed spaces to receive the 80 date, the source from which received and the consideration, for all deposits made during the using of the checks attached to said leaf, the stub having lines upon the opposite side 85 thereof for additional memoranda; substantially as described.

5. A check-book having stubs, each stub bearing a form having appropriately-designed spaces to receive collected data relating to a number of checks, and another form 90 vertically separated therefrom, and having appropriately-designed spaces to receive collected data for a number of deposits; substantially as described.

6. A book having stubs bearing a form 95 having appropriately-designed spaces to receive collected data relating to a number of checks, said form filling only a part of the width or vertical height of the stub, and another form on the same face of the stub 100 and vertically separated from the check form; substantially as described.

In testimony whereof I have hereunto set my hand.

FREDERICK McCORMICK.
